UNITED STATES PATENT OFFICE.

HENRY J. TAYLOR, OF BOSTON, MASSACHUSETTS.

COMBINATION RULER AND BLOTTER.

1,078,969.

Specification of Letters Patent.

Patented Nov. 18, 1913.

Application filed January 23, 1912. Serial No. 672,837.

To all whom it may concern:

Be it known that I, HENRY J. TAYLOR, a citizen of the United States, residing at Boston, in the county of Suffolk and State of Massachusetts, have invented new and useful Improvements in Combination Rulers and Blotters, of which the following is a specification.

An object of the invention is to provide 10 a combined ruler and blotter, the blotter being removable for the purpose of replacing the same with a new blotter when the old blotter becomes worn. For the purpose mentioned, use is made of a body member 15 having inclined sides and adapted to be engaged on the under side by a blotter strip, with the edges of the blotter strip extending over the inclined sides of the body member and a ruler plate provided with inclined 20 sides and adapted for slidable engagement with the body member so that the edges of the said blotter strip will lie between the inclined sides of the body member and the inclined sides of the ruler plate, thus rigidly retaining the blotter strip in engagement with the said body, the edges of the 25 said ruler plate being arranged to form straight edges conveniently adapted for ruling purposes.

30 In the further disclosure of the invention, reference is to be had to the accompanying drawings constituting a part of this specification, in which similar characters of reference denote corresponding parts 35 in all the views, and in which—

Figure 1 is a perspective view of my device. Fig. 2 is a fragmentary perspective view showing the ruler plate partially removed from the body member, which is arranged to form a container. Fig. 3 is a vertical transverse sectional view on the line 3—3 in Fig. 1. Fig. 4 is a perspective view of a modified form of my device. Fig. 5 is a vertical transverse sectional view taken on 45 the line 5—5 in Fig. 4.

Referring to Figs. 1 to 3 inclusive, illustrating the preferred form of my device, I employ a body member 10, formed of an integral piece of material and having inclined 50 sides 11 and ends 12, arranged to form a container 13. A blotter strip 14 is mounted to extend along the under side of the body member 10 with the longitudinal edges of the blotter strip overlapping the inclined 55 sides or edges 11 of the body member 10 and mounted for slidable engagement with the

body member 10 is a ruler plate 15 provided with downwardly extending inclined edges 16, the mentioned blotter strip 14 being so arranged upon the body member 10 that the 60 longitudinal edges of the blotter strip will lie between the inclined edges 11 of the body member 10 and the inclined edges 16 of the ruler plate 15 thus rigidly retaining the blotter strip 14 in engagement with the body 65 member.

The ruler plate 15 is preferably formed of an integral piece of material, bent to form a longitudinally extending handle 17 from which portions of the plate extend upwardly at an angle, their outer ends being curved to form the downwardly extending edges 16. By referring to Fig. 2, it will be seen that the ruler plate 15 not only acts as a means for retaining the blotter strip in 70 engagement with the body member 10, but also acts as a cover for the container 13, in which suitable pens, stamps or other articles can be conveniently placed.

A straight edge 18, formed at the point 80 of bending of one of the inclined edges 16 of the ruler plate 15 can be conveniently employed to insure the ruling of straight lines and formed integrally with the lower end of the other inclined edge 16 of the ruler plate 85 15 is an outwardly projecting plate 19, having the outer edge thereof sharpened to form a cutting edge, a series of graduations being preferably provided on the plate 19 for the purpose of measuring off various 90 distances, the cutting edge formed on the plate being adapted for cutting or tearing sheets of paper and the like.

Mounted to swing at one end of the ruler plate 15 is a paper cutting knife blade 20, the said knife blade being so arranged upon the ruler plate that when the knife blade is in open position a portion of the rear edge thereof will abut against the handle 17 so that the handle will form a stop member 100 to limit the outward swinging movement of the knife edge, the mentioned knife edge when in closed position being adapted to lie within the plane of the straight edge 18, as shown in dotted lines in Fig. 1.

From the foregoing description it will be seen that in my device is embodied a blotting element, a container and a ruler plate provided to form a cover for the container, a straight edge, a scale and a cutting edge, a 110 knife blade being mounted to swing on the ruler plate and adapted to have its outward

swinging movement limited by the handle of the ruler plate. When it is desired to provide a new blotter strip for my device, the ruler plate 15 is slidably disengaged from 5 the body 10 and a new blotter can then be very easily placed in blotting position on the body 10 as will be readily understood.

In Figs. 4 and 5 I disclose a modified form 10 of my device, constructed upon the same principle as the device disclosed in Figs. 1 to 3 inclusive with the exception that minor details are omitted for the purpose of producing a simple and effective combined blotter and ruler. The modified form of my device resides in a body 21 having inclined sides 22 and adapted to receive a blotter strip 23, the edges of which overlap the inclined edges 22 of the body 21. The body 21 is preferably made of a solid piece of material 15 and mounted to slidably engage the same is a ruler plate 24, having inwardly extending inclined edges 25 arranged so that the blotter strip 23 will be interposed between the edges 22 of the body 21 and the 20 inwardly inclined edges 25 of the ruler plate 24, thus retaining the blotter strip 23 in engagement with the blotter. By inclining the edges 25 inwardly, suitable ruling or straight edges 26 are provided and if desirable, suitable 25 graduations 27 can be provided adjacent the straight edges 26, thus greatly adding to the appearance of the device and producing a more practical article of manufacture.

I claim:—

35 1. As a new article of manufacture, a combined ruler and blotter comprising a body formed of a single piece of material having upwardly inclined sides forming a container

and adapted to receive a blotter inclosing the said container, a ruler plate formed of a single piece of material bent to provide downwardly inclined sides and adapted to slidably receive the said body to form a cover for the container and secure the ends of the blotter between the inclined sides of the body and the inclined sides of the ruler plate, and a handle formed integrally with the ruler plate by striking upwardly a medial longitudinal portion thereof, the said handle extending longitudinally to the said plate and throughout its entire length.

2. As a new article of manufacture, a combined ruler and blotter comprising a body formed of a single piece of material constituting a container and adapted to receive a blotter in closing the container, with the edges of the blotter projecting upwardly adjacent the sides of the container, a ruler plate formed of a single piece of material and adapted to slidably receive the said body to form a cover for the container, with the longitudinal edges of the blotter interposed between the sides of the said container and the said cover, a handle formed integrally with the ruler plate and extending longitudinally thereto, and an integral graduated plate projecting horizontally from one side of the said cover and extending longitudinally thereto throughout its entire length.

In testimony whereof I affix my signature 70 in presence of two witnesses.

HENRY J. TAYLOR.
